UNITED STATES PATENT OFFICE.

WILLIAM H. SMITH, OF BUFFALO, NEW YORK.

DESIGN FOR A SPROCKET OR SIMILAR ARTICLE.

SPECIFICATION forming part of Design No. 31,365, dated August 8, 1899.

Application filed June 30, 1899. Serial No. 722,468. Term of patent 31 years.

To all whom it may concern:

Be it known that I, WILLIAM H. SMITH, a citizen of the United States, and a resident of Buffalo, in the county of Erie and State of New York, have invented and produced a new and original Design for Sprockets or Like Articles for Bicycles, of which the following is a specification, reference being had to the accompanying drawing, forming a part thereof, in which is illustrated a plan view of my new design.

The leading feature of my design made the subject of illustration resides in the arrangement of a series of arms 1, having sides 2, of

waving or curving formation, radially around a center portion 3, with their outer ends extending to a concentrically-arranged circular outer ring 4.

Having described my invention, what I claim as new, and desire to secure by Letters Patent, is—

The design for a sprocket or similar article, as herein shown and described.

WM. H. SMITH.
